SELECTIVE FLUID VALVE

John H. T. Millington, Hamilton, Ontario, Canada, assignor to Westinghouse Electric & Manufacturing Company, East Pittsburgh, Pa., a corporation of Pennsylvania

Application February 14, 1942, Serial No. 430,923

10 Claims. (Cl. 277—3)

This invention relates to valve means regulating the flow of fluids in a conduit, and more particularly to a multi-valve means for regulating simultaneously the flow of fluids in a plurality of conduits.

One of the objects of the present invention is to provide a multi-valve means for regulating simultaneously the flow of fluids in a plurality of conduits.

Another object is to provide a means for regulating simultaneously the flow of fluids in a plurality of conduits, said means being adjustable to obtain any desired relative proportioning of the fluids in the said conduits.

Still another object is to provide an adjustable valve means adapted particularly to regulate the relative volumes of the elastic fluids of air, gas and oxygen passing from separate supply conduits through the valve means to a burner.

Other objects and advantages will be apparent as the invention is more fully hereinafter disclosed.

In accordance with the above objects I have devised the multi-valve means illustrated in the accompanying drawings which, as a specific embodiment of the present invention, illustrates a valve means particularly adapted for the regulation and control of the relative volumes of the elastic fluids, air, gas and oxygen, passing through the valve means to a burner, thereby to obtain at the burner a desired flame within a range of flames known in the art as a pilot flame to a high temperature flame.

In the art of working glass, for example, it is frequently necessary to vary the flame at the burner from a small pilot flame to a sharp high temperature flame and to intermediate types of flames between these two extremes. Such a variation of flame is obtained by regulating the relative volumes of air, gas and oxygen passing in admixture to the burner. For example, a small pilot flame is obtained by a reduced volume of gas passing to the burner; a soft brush flame is obtained with a greater volume of gas; a medium hard flame is obtained by mixing a small amount of air with the gas passing to the burner; a hard fire is obtained by mixing still more air with the gas passing to the burner; and a sharp or needle high temperature flame is obtained by mixing oxygen with the air-gas mixture which was used to produce the hard fire flame.

The manual control of the relative volumes of air, gas and oxygen to produce the several types of flames above identified is inexpedient and time consuming, and heretofore in the art various

means have been proposed to automatically control such gas mixtures. None of the means heretofore provided, however, have been entirely satisfactory for the primary reason that no easy

5 manual adjustment of the means to compensate for variations in air, gas and oxygen pressures or for variations in the calorific value of the gas has been provided. The present invention provides such a manually operative adjustment of the

10 multi-valve means in combination with a different type of valve means, per se, than has heretofore been employed in the art, insofar as I am aware.

Referring to the drawings, I have illustrated in eight figures a preferred arrangement of the present invention designed particularly for the control and regulation of the relative volumes of the gases (air, oxygen and illuminating gas) passing in admixture to a burner of a type employed in

15 the glass working art. As the burner, per se, forms no part of the present invention, the details thereof have not been illustrated nor has the manner in which the present invention is associated therewith been shown as the same is

20 obvious to one skilled in the art.

25 In the drawings:

Figure 1 is a plan of the valve means of the present invention.

Figure 2 is a side elevational view of the same.

30 Figure 3 is a vertical sectional view on the line III—III of Figure 2 in the direction of the arrows.

Figure 4 is a horizontal sectional view on the line IV—IV of Figure 2.

Figure 5 illustrates five different positions of the valve parts adjusted a certain way.

35 Figure 6 is a side elevational view of a modification of my valve operating means.

Figure 7 is an end elevational view of the same.

Figure 8 is a horizontal sectional view taken on the line VIII—VIII of Figure 7.

40 The valve means of the present invention comprises a plurality of cylinders assembled with their respective axes substantially parallel and coplanar, and a plurality of pistons, one for each cylinder, with oppositely aligned inlet and outlet ports in each cylinder wall preferably lying in the same horizontal plane, cross-hole passageways in each piston, and manually operative

45 means to selectively locate the cross-hole passageways in each piston relative to the ports of each cylinder to provide either full closure of the ports, full opening of the said ports, or a predetermined partial opening of the said ports, thereby to obtain any desired volume relation between the

50 way of each piston relative to the ports of each cylinder to provide either full closure of the ports, full opening of the said ports, or a predetermined partial opening of the said ports, thereby to obtain any desired volume relation between the gases supplied to each cylinder inlet port in the

conduits conducting the gases away from each cylinder outlet port opening.

It is customary in the art to supply the gases (air, oxygen and illuminating gas) to the valve means under pressure for passage therethrough to the burner, and to regulate and control the relative volumes of the gases passing through the valve means to the burner by manually adjusting the valve means to permit the desired volume of each gas to pass the said valve means. Variations in the pressures of the said gases and in the calorific value of the illuminating gas supplied to the valve make it difficult with any type of valve means to obtain consistent gas mixtures at the burner by any mechanical means to obtain a predetermined position of the valve means.

The manually operative means to selectively locate the piston cross-hole passageways with respect to the cylindred inlet and outlet port hole openings includes also means to adjust the particular setting on each piston so that variations in gas pressures and in the illuminating gas calorific value may be readily and easily compensated.

Referring to the drawings, the valve means of the present invention comprises three cylindrically-shaped valve chambers (C₃, C₂ and C₁) one for each of the gases air, oxygen and illuminating gas. Preferably the three chambers (C₁, C₂ and C₃) are positioned with their axes lying in parallel spaced relation in substantially the same vertical plane, as shown. Most simply, this arrangement is provided by forming three substantially parallel cylindrical holes in a body portion B. Aligned opposite inlet and outlet port openings i₁, i₂, i₃ and o₁, o₂ and o₃, respectively lying in substantially the same horizontal plane, are provided in each chamber wall. Pistons P₁, P₂ and P₃, respectively, are provided for each chamber C₁, C₂ and C₃ and cross-hole passageways h₁, h₂ and h₃ are provided in each piston P₁, P₂ and P₃, respectively.

Spring means S₁, (S₂, S₃) is provided in the bottom of each chamber C₁ (C₂, C₃) to urge each piston P₁ (P₂, P₃) upwardly in each chamber, and stop means K₁ and K₃ are provided at the top of chambers C₁ and C₃ to respectively engage shoulders L₁ and L₃ on pistons P₁ and P₃, respectively, to hold said pistons in a position locating the respective cross-holes h₁ and h₃ in full open position across the port holes i₁, o₁ and i₃, o₃, respectively.

Piston P₂ has a length considerably greater than the lengths of pistons P₁ and P₃, and carries on the extending end thereof manually-operative valve actuating means and the manually-operative valve adjusting means.

The manually-operative valve actuating means comprises essentially lever means M to selectively move the pistons P₁, P₂ and P₃ in opposition to the spring means S₁, S₂ and S₃ from the advanced position indicated in the drawings (Figs. 1 to 4, inclusive), wherein each cross-hole opening of pistons P₁, P₂ and P₃ are in full open position with respect to the chamber port holes, to a position wherein each cross-hole piston opening is in full closed position with respect to the chamber port holes and to a plurality of intermediate desired positions of partial closure whereby desired mixtures of the gases air, oxygen and illuminating gas, passing through the valve means to the burner, are obtained.

The specific arrangement to accomplish this desired result may be varied widely without essential departure from the present invention. In

the arrangement shown in Figures 1 to 5, inclusive, the means is designed to provide a plurality of predetermined positions of the pistons thereby to obtain a plurality of flame conditions at a burner used in the art of working glass.

As indicated in the drawings, the center piston P₂ extends beyond the top of the valve a sufficient distance to provide for the attachment at the end thereof of lever means M for reciprocating the piston within chamber C₂ and to provide also for the adjustable attachment thereto of cross-bar means 10 with sufficient clearance therebelow to permit reciprocation of the piston P₂ within its chamber. On the ends of cross-bar 10, which forms arms projecting laterally from the piston P₂, are set screws 13 and 14 provided in a position so that their ends, in effect, forming adjustable fingers, engage the heads of pistons P₁ and P₃ upon reciprocation of the piston P₂, as by the lever means M provided on the end thereof.

By varying the adjustment of the set screws 13 and 14, the precise positions of engagement of the piston heads P₁ and P₃ may be varied to obtain a wide variety of operation sequences. By varying the location of cross-bar 10 on the end of piston P₂, as by shifting the same vertically therealong, and then tightening set screw 11 in groove 12, further control and regulation of the operational sequence of the valve means of the present invention may be obtained.

Lever M is pivotally secured to the end of the piston P₂ by means of pin 15 riding loosely in elongated opening 16, with one end of the lever 35 pivotally mounted on shaft 17 held by arm 18, in turn carried by base B and with the other end of lever M extending beyond the piston P₂ a sufficient distance to permit manual actuation of the same by an operator.

To provide for placing the pistons with the cross-hole passageways thereof in a plurality of locations intermediate fully open and fully closed positions, the extending free end of lever M may be provided with any desired type of shift-lock means equivalent functionally to the shift-lock means shown.

The shift-lock means shown comprises a spring clip member 20 secured onto the free end of lever M and a notched member T mounted on base B in a position, relative to the path of travel of the spring clip member 20, to provide a trackway for the said spring clip member 20, the notches numbered 1 to 5, inclusive, on said trackway T, for example, providing for a plurality of predetermined intermediate positions for the pistons between fully opened position and fully closed position, the latter position being obtained when the piston P₂ has been moved in opposition to spring means S₂ to a position bringing the spring clip member 20 in engagement with the groove marked "off" in trackway T.

As a specific example of one adjustment of the valve of the present invention, reference should be had to Figure 5, wherein in five (5) figures is shown the sequence of operating position of the valve conforming to the grooves 1 to 5, inclusive, in trackway T (Fig. 3).

When the piston P₂ is moved, by knob N, to a position bringing spring clip member 20 in engagement with notch 1 on trackway T, the adjustment of set screw 13 on collar 10 secured on the extension of piston P₂, is such as to permit the spring means S₁ to urge piston P₁ to a position wherein the cross-hole opening h₁, therein is about $\frac{1}{4}$ open across the port holes i₁, and o₁ in

the walls of chamber C_1 , while both of the cross-holes h_2 and h_3 remain in a position below the respective port hole openings. When the illuminating gas supply is controlled by this chamber, this provides merely a sufficient amount of gas to the burner to support a small pilot flame.

When the piston P_2 is raised to the position indicated by the engagement of spring clip member 20 in notch 2 , spring means S_1 urges piston P_1 to a position bringing the cross-hole passageway h_1 to a position where the inlet and outlet openings i_1 and o_1 are about $\frac{1}{2}$ open while the ports of both chambers P_2 and P_3 remain closed. This provides a larger supply of gas to the burner forming what is known as a "soft brush" flame.

When the piston P_2 is raised to the position indicated by the engagement of spring clip member 20 in notch 3 , spring means S_1 has moved piston P_1 to full open position wherein it is held by stop means $K-1$, and spring means S_3 has moved piston P_3 to a position wherein ports i_3 and o_3 in the walls of chamber C_3 are about $\frac{1}{2}$ open, thereby permitting air from a pressure supply source (not shown) to pass to the burner in admixture with the gas passing through the port openings in chamber C_1 . This provides an air-gas mixture giving a "medium hard" flame. As the relative pressures of the air and gas may vary from time to time or the calorific value of the gas change somewhat, the precise relative proportioning of this air-gas mixture may be adjusted by movement of set screw 14 in collar 10 up or down, thereby increasing or decreasing the air ratio at this particular setting to obtain the desired "medium hard" flame.

When the piston P_2 is moved to the position indicated by the engagement of spring clip member 20 in notch 4 , spring means S_3 has urged piston P_3 to a position bringing cross-hole h_3 to full open position across port holes i_3 and o_3 in chamber C_3 . Further movement of the piston P_3 is restrained by stop K_3 , but cross-hole h_2 in piston P_2 , however, has not yet been moved to a position permitting the flow of oxygen through the port openings i_2 and o_2 of cylinder C_2 . This position gives a "hard" fire under the usual air-gas pressures employed in such burners.

Further movement of piston P_2 to a position bringing spring clip member 20 in engagement with the notch 5 brings the cross-hole h_2 in open position across port openings i_2 and o_2 in chamber C_2 permitting oxygen under pressure to pass in admixture with the gas-air mixture from chambers C_1 and C_3 to the burner, thereby producing a high temperature flame known generally as a "sharp needle" flame at the burner.

Such an arrangement as hereinabove described and as illustrated in the drawings Figures 1 to 5, inclusive, affords a simple and effective control and regulation of the gas-air-oxygen mixtures commonly employed in the art of glass working. Where the gas, air and oxygen pressures in the supply conduits leading to the valve means of the present invention are excessive, pressure reducing or pressure regulating valves may be interposed.

Where it is desired to have a more flexible control of the air, gas and oxygen mixtures passing to the burner, the arrangement illustrated in Figures 6 to 8, inclusive, or its functional equivalent may be employed. In this arrangement, the reciprocation of piston P_2 is effected by a rack and gear arrangement, the rack R being located on an extension of the piston P_2 and the gear G being located as a segment on a manually rotatable

wheel W mounted on bearing arm 30 . To provide for holding the manually actuated pistons P_1 , P_2 and P_3 in any position, means such as spring clip member 31 engaging the knurled peripheral surface of the wheel W may be provided.

With this arrangement, by varying the adjustment afforded by set screws 13^a and 14^a and the point of location of cross-bar 10^a on the extension of piston P_2 a wide range of gas-air-oxygen mixtures may be obtained, as one skilled in the art will readily recognize.

From the above description and the drawings illustrating one specific embodiment of the multi-valve means of the present invention and a modification of the same, it is believed apparent that many modifications and adaptations of the same may be made in the control and regulation of flow of fluids generally, without essential departure therefrom, and all such modifications and adaptations are contemplated as may fall within the scope of the following claims:

I claim:

1. In a valve for regulating the flow of fluids in conduits to mix them in selected proportions, a plurality of cylindrical valve chambers provided with oppositely aligned inlet and outlet port openings in the side walls thereof, a piston provided with a cross-hole therethrough and disposed in each chamber, means to adjustably locate each piston in its cylinder to dispose the said cross-hole in open and closed positions relative to said port openings and to intermediate partially opened positions therebetween, resilient means to urge said pistons against said locating means, means to limit movement of each piston by its resilient means beyond its full open position, and adjustable means to simultaneously operate said pistons.
2. In a valve regulating the flow of fluids in conduits to mix them in selected proportions, a plurality of cylindrical valve chambers each having opposite aligned inlet and outlet port openings in the side walls thereof, a piston member slidably mounted in each cylindrical chamber, said pistons being provided with cross-holes therethrough, means to adjustably locate the said pistons in the said chambers with the cross-holes disposed relative to the said port openings within the range of positions lying between fully opened to fully closed, resilient means to urge said pistons against said locating means, means to limit movement of each piston by its resilient means beyond its full open position, and adjustable means to simultaneously operate said pistons.
3. In a valve for regulating the flow of fluid in a plurality of conduits, a plurality of cylindrically-shaped valve chambers each provided with opposite aligned inlet and outlet ports communicating with separate fluid conduits, a cylindrically-shaped piston in each chamber, provided with a cross-hole therethrough, and means to selectively position each of the plurality of pistons within their chambers, with the said cross-hole of each piston in a desired position relative to the associated port openings, within the range between fully open to fully closed positions, said means including an arm projecting from one of said pistons and carrying an adjustable finger for engagement with another piston.
4. In a valve for regulating the flow of fluid in a plurality of conduits, a plurality of cylindrically-shaped valve chambers sustained in parallel spaced relation, each chamber being provided with opposite aligned inlet and outlet ports

communicating exteriorly with separate fluid conduits, a cylindrically-shaped piston in each chamber provided with a cross-hole therethrough to communicate with the inlet and outlet of the chamber when the said piston is located in one position in said chamber, to close the said ports when the said piston is moved to a second position in said chamber and to partially open said ports when the said piston is moved to intermediate positions therebetween, and manually operative means to selectively move the pistons to any desired position within the said range of positions above identified, said means including an arm projecting from one of said pistons and carrying an adjustable finger for engagement with another piston.

5. In a valve for regulating the flow of fluid in a plurality of conduits, a plurality of cylindrically-shaped valve chambers one for each conduit, inlet and outlet ports oppositely aligned in the side walls of each chamber and communicating exteriorly with said conduits, a cylindrically-shaped piston in each chamber, each piston being provided with a cross-hole therethrough to communicate with the said ports when the piston is located in one position in its chamber, to not communicate therewith when the piston is located in a second position in its chamber, and to partially overlap therewith at intermediate positions therebetween, and adjustable means to move manually the said pistons selectively to obtain any desired relative volume of fluid passing through the said valve in each conduit, said means including an arm projecting from one of said pistons and carrying an adjustable finger for engagement with another piston.

6. Valve means for regulating the flow of fluid in a plurality of conduits, comprising a plurality of axially parallel spaced cylindrically-shaped valve chambers, one for each conduit, oppositely aligned inlet and outlet ports in the side walls of each of said chambers, a cylindrically-shaped piston for each chamber having a cross-hole therethrough which in one position of the said piston in the chamber provides a passageway for fluid through the said piston from the inlet to the outlet port of the said chamber, in a second position does not provide such a passageway, and at intermediate positions therebetween provides a partially opened passageway for said fluid, and means to selectively position each piston in its chamber within the range of positions above stated to provide any desired ratio between the volume of fluid passing through the separate valve chambers, said means including an arm projecting from one of said pistons and carrying an adjustable finger for engagement with another piston.

7. The combination of claim 6, wherein the said means to selectively position the said pistons is manually adjustable with respect to each piston and manually operative with respect to all of said pistons by a common operating element.

8. The combination of claim 6, wherein the said means to selectively position said pistons

comprises in combination spring means slidably and independently actuating each piston in one direction, lever means manually operative to actuate one of said pistons slidably in opposition to the spring means thereof, and adjustable cross-bar means movable with said lever-actuated piston and carrying adjustable means to selectively actuate the other pistons in opposition to the said spring means.

10. Multiple valve means for regulating the relative amounts of air, gas and oxygen passing from separate supply conduits under pressure to a burner, said valve means comprising three parallel spaced cylindrically-shaped valve chambers having their axes coplanar and with oppositely aligned inlet and outlet ports in the side walls thereof, with all of the said openings lying substantially in the same plane transverse to the cylindrical axes of the chambers, a cylindrically-shaped piston for each chamber having a cross-hole therethrough, spring means in the bottom of each chamber to urge the pistons therein upwardly, stop means at the top of each end chamber to limit the upward movement of the two end pistons to a position bringing the cross-hole of each to open position across the port openings in the respective chamber walls, an extension on the upper end of the middle piston, and means to manually reciprocate the said piston within its chamber, from a position wherein the said cross-hole therein is in fully opened position relative to the inlet and outlet port openings of its chamber to a lower position wherein the said cross-hole is remote from said fully opened position, a cross-bar and means to adjustably secure the same to the extending end of said middle piston with its ends overlaying the heads of the end pistons, and adjustable set screw means on each end extending downwardly towards the heads of said end pistons in a position to engage said heads as the said middle piston is moved downwardly, thereby to move the said end pistons downwardly within the said end chambers in opposition to the spring means, and means to secure the said pistons in any desired position of downward movement between said fully opened to fully closed position of each piston.

10. Valve means for a plurality of conduits comprising one valve cylinder for each conduit, each cylinder having aligned inlet and outlet ports in opposite sides thereof and communicating with the respective conduits, a piston reciprocable in each cylinder and having a transverse port adapted to move into and out of alignment with said inlet and outlet ports to open to a desired extent or close said ports, means for directly reciprocating one of said pistons in its cylinder, a cross member carried by said piston, and adjustable means carried by said cross member and operatively associated with another piston, so that the reciprocating means may move and selectively position said pistons within their cylinders to provide for a desired sequence in regulating the flow of fluid through said valve means.

JOHN H. T. MILLINGTON.
